UNITED STATES PATENT OFFICE.

FREDERICK HYDE, OF PHILADELPHIA, PENNSYLVANIA, ASSIGNOR TO MOSES L. BLOCH,
OF PHILADELPHIA, PENNSYLVANIA.

GO-CART.

1,157,224.

Specification of Letters Patent.

Patented Oct. 19, 1915.

Application filed October 1, 1914. Serial No. 864,410.

To all whom it may concern:

Be it known that I, FREDERICK HYDE, a citizen of the United States, residing at Philadelphia, county of Philadelphia, and 5 State of Pennsylvania, have invented a new and useful Improvement in Go-Carts, of which the following is a full, clear, and exact description, reference being had to the accompanying drawings, which form a part 10 of this specification.

The object of my invention is to provide a go-cart or baby carriage, the body of which may be directly supported upon springs and which is capable of being reversed so as to 15 bring either end of the body nearest the handle bar by which the vehicle is pushed. While constructions permitting the reversal of a carriage body are known in the art, it is desirable to construct the reversing mechanism as a part of the running gear, but this 20 has been deemed impracticable owing to the obstruction offered by the wheels which extend above the level of the running gear. In my invention, the desired result has been 25 secured while maintaining the normal level of the running gear, means being provided to elevate a part of the gear to permit of the reversal of the spring frame for immediately supporting the body and provision 30 being made for holding the vertically movable frame, whether in its raised or lowered position, in rigid relation to the remainder of the running gear.

A preferred embodiment of my invention 35 is shown in the accompanying drawings, in which—

Figure 1 is a side elevation of the go-cart with the body in normal position and at the 40 normal elevation. Fig. 2 is a similar view with the body elevated and reversed. Fig. 3 is a plan of the running gear with the body supporting frame in a transitional position. Fig. 4 is a front view of the running gear with the vertically movable part 45 thereof in raised position. Fig. 5 is a section on the line 5—5 of Fig. 2 showing a partial rear view of the running gear. Fig. 6 is a section on the line 6—6 of Fig. 2.

Between the axles a, a , carrying the wheels 50 b extend fixed side bars c, c , one at each side.

Directly above the side bars is a vertically 55 movable lower frame comprising longitudinally extending side bars d, d ; longitudinally extending spring bars e, e , the ends of

which are curved downward and riveted respectively to the front and rear of the corresponding bars d, d ; cross bars f, f , connecting bars e, e , and a central longitudinally extending bar g connecting cross bars 60 f, f .

The frame $d e f g$ is movably connected to the side bars c, c , at the rear by means of links h, h , and at the front by means of the ends i, i , of the two arms of a yoke lever j . 65

By depressing the yoke end of lever j , the frame $d e f g$ may be elevated as shown in Fig. 2. By lifting the lever j , the frame $d e f g$ is depressed into the normal position shown in Fig. 1. 70

h, h , are stops limiting the movement of the lever j in the lifting movement of the frame $d e f g$. These stops are secured at the front ends of bars c, c , immediately back of the pivots of lever j . 75

The handle bar frame n is secured to brackets l on the rear axle and at its front end to brackets m on the side bars c . Preferably the brackets m are so located that the bars d will frictionally engage therewith so 80 as to offer some resistance to the elevation of the frame $d e f g$.

The frame for immediately supporting the body comprises longitudinally extending side bars o , cross-bars p, p , and a central longitudinally extending bar r . The front and rear ends of the side bars o, o , are 85 curved to form spring members to which the body s of the car is directly connected.

The bar r at its center is pivotally supported on the bar g of the intermediate vertically movable frame to enable the body to be turned in a horizontal plane. 90

A longitudinally extending spring bar t , riveted at its front end to the front cross bar f and to the front end of bar g , extends immediately under the bar g and terminates behind the rear cross bar f . Secured to the spring bar t immediately in front of the rear cross bar f is a cam-latch comprising a transversely extending plate having rear upwardly-extending flanges v extending on opposite sides of the bar g and also on opposite sides of the bar r when the body supporting frame occupies its normal position, thereby locking the body from reversal. 95 100 105

To reverse the body, the yoke of the lever j is depressed, thereby elevating the lower frame $d e f g$ and with it the upper body supporting frame $o p r$ so as to raise the level 110

of the latter entirely above the cart wheels *b*. The rear end of spring bar *t* is then depressed so as to lower the flanges *v* below the level of the bar *r*. Thereupon the body supporting frame is unlocked and may, with the body, be completely reversed.

As soon as the movement of reversal has been started, the spring locking lever *t* may be released. As the movement of reversal is completed the bar *r* engages the cam edge of one of the flanges *v* and depresses the spring locking-bar *t* until the bar *r* overrides the flange, whereupon the bar *t* springs into locking position. The yoke end of the lever *j* is then raised, thereby lowering the lower frame, the body supporting frame and the body into normal position.

Having now fully described my invention, what I claim and desire to protect by Letters Patent is:

1. A go-cart comprising axles and wheels, a lower frame, an upper frame, a body supported on the upper frame, the upper frame being pivoted on the lower frame so as to turn thereon horizontally, and lifting means connecting the lower frame with the axles and adapted to be operated to raise the lower frame from its normal lower position to enable the upper frame when turned to clear the tops of the wheels.

2. A go-cart comprising axles and wheels, a body, a lower frame, an upper frame pivoted on a vertical axis centrally of the lower frame and comprising side bars curved front and rear to afford a spring support for the body, and lifting means connecting the lower frame with the axles and adapted to be operated to raise the lower frame from its normal lower position.

3. A go-cart comprising axles and wheels, side bars rigidly connecting the axles, a lower frame above the side bars, parallel links connecting the side bars and the lower frame, an upper body-supporting frame pivoted on the lower frame so as to turn thereon horizontally, and means to move the links toward either a horizontal or a vertical position, thereby moving the lower part of the upper frame either below the level of the tops of the wheels or above that level, thus permitting the upper frame to be turned on its pivot when elevated.

4. A go-cart comprising axles and wheels, side bars rigidly connecting the axles, a lower frame above the side bars, links pivotally connected to the rear portions of the side bars and lower frame, a lever the ends of which extend parallel to the rear links and are pivotally connected to the front portions of the side bars and lower frame, and an upper body supporting frame pivoted on a vertical axis centrally of the lower frame.

5. A go-cart comprising axles and wheels, side bars rigidly connecting the axles; a lower frame comprising lower and upper

side bars connected at front and rear, cross-bars connecting the last named side bars, and a longitudinally centrally extending bar connecting the cross bars; an upper frame comprising side bars, spring body supporting members connecting with the last named side bars at front and rear, cross bars connecting the last named side bars, and a longitudinally centrally extending bar connecting the last named side bars and pivotally supported on the longitudinally extending bar of the upper frame; and means connecting the lower frame with the axle and permitting it to be raised from its normal depressed position.

6. A go-cart comprising axles and wheels, a lower frame including a longitudinally extending central bar, means connecting the lower frame with the axles and permitting it to be raised and lowered, an upper body-supporting frame including a longitudinally extending central bar pivotally supported on the first bar, a spring pressed manually operable latch on one bar normally engaging the other bar and holding the upper frame from turning, said latch provided with a cam face adapted to be engaged by the last named bar as the upper frame completes its turning movement whereby the latch is temporarily moved out of operative position in the completion of the turning movement.

7. A go-cart comprising axles and wheels, a lower frame including a longitudinally extending central bar, means connecting the lower frame with the axles and permitting it to be raised and lowered, an upper body-supporting frame including a longitudinally extending central bar pivotally supported on the first bar, a latch comprising two flanges normally extending on opposite sides of the second bar and thereby holding the upper frame from turning, means to support said latch and permit it to be depressed to allow the upper frame to be turned, said flanges having cam edges one or the other of which is adapted to be engaged by the second bar as the upper frame completes its turning movement, whereby the latch is depressed to permit completion of the turning movement.

8. A go-cart comprising axles and wheels, a lower frame including a longitudinally extending central bar, means connecting the lower frame with the axles and permitting it to be raised and lowered, an upper body-supporting frame including a longitudinally extending central bar pivotally supported on the first bar, a spring bar secured at its front end to the lower frame and extending under both said bars, a plate carried by the spring bar having flanges extending on opposite sides of the first two bars, the two flanges having edges converging upward.

9. A go-cart comprising axles and wheels, side bars rigidly connecting the axles, a lower frame above the side bars, links pivot-

ally connected to the rear portions of the side bars and lower frame, a lever the ends of which extend parallel to the rear links and are pivotally connected to the front portions of the side bars and lower frame, stops secured to the side bars adjacent to the pivotal connections of said lever and adapted to limit the movement of the latter in the elevation of the lower frame, and an upper frame pivoted on the lower frame to permit it to turn thereon.

10. A go-cart comprising axles and wheels, side bars rigidly connecting the axles, a lower frame above the side bars, parallel links connecting the side bars and the lower frame, an upper body supporting frame

turnable on the lower frame, means to move the links toward either a horizontal or a vertical position, a handle bar frame, supporting brackets rigidly connecting the handle bar frame with the side bars, opposite links being arranged to frictionally engage said brackets when the links are moved toward a horizontal position.

15 In testimony of which invention, I have hereunto set my hand, at Philadelphia, on this 29th day of September, 1914.

FREDERICK HYDE.
